UNITED STATES PATENT OFFICE.

WILLIAM P. LEVY, OF SPRECKELS, CALIFORNIA.

WHIPPING GOLF CLUBS OR THE LIKE.

Application filed May 13, 1926. Serial No. 103,962.

In the ordinary construction of golf club shafts or handles it is frequently customary to wrap a strip of leather spirally around the shaft, this leather being glued or otherwise suitably secured at one end, and the free end of the leather being retained in place by a whipping, seizing or serving encircling the leather and the shaft.

As this whipping or wrapping is now employed, severance of a single convolution of the whipping will cause the entire whipping cord to unravel or unwind, thereby rendering the same useless.

In accordance with the present invention I so whip the leather that the severance of one convolution of the whipping cannot cause unwinding or unravelling of the other convolutions thereof, inasmuch as each convolution is interlocked with adjacent convolutions in such a manner that unwinding of more than one convolution is impossible.

A further object of the invention is to provide a whipping which may be applied rapidly and at no material increase in cost over the whippings now commonly employed.

Further objects of the invention are to provide a golf club embodying the present invention which will be of simple, practical construction, rugged, and durable in use, and of neat and attractive appearance.

With the above noted and other objects in view, the invention consists in certain novel features of construction and combinations and arrangements of parts, as will be more fully hereinafter set forth and pointed out in the claims. The invention may be more fully understood from the following description in connection with the accompanying drawings, wherein—

Fig. 1 is a view in side elevation of a golf club shaft showing the leather wrapping retained in place by a whipping cord applied in accordance with the present invention.

Fig. 2 is an enlarged detail view showing the manner in which the cord is wrapped and twisted about the shaft.

Fig. 3 is a further enlarged detail showing two convolutions of the whipping cord, and the manner in which each individual convolution is locked against unwinding.

Fig. 4 is a small view in side elevation illustrating a whipping embodying the present invention in which the knots of the suc-

cessive convolutions of the whipping cord produce spiral ribs on the whipping.

In the drawings, I have used the reference character 10 to designate the shaft of a golf club, about the upper end of which is spirally wound a leather strip 11. Strip 11 may be glued or otherwise anchored to the upper end of the shaft and at its lower end is secured by a series of laterally adjacent convolutions of whipping 12 overlapping the lower end of the leather strip and retaining the same against unwinding or against longitudinal displacement on the shaft.

The present invention is primarily concerned with the manner in which this whipping is applied, and with the provision of a whipping which will not become unwound if one convolution thereof is inadvertently severed.

The ordinary method of whipping is to anchor one end of the whipping cord, wrap the cord around the shaft, and the leather strip in a series of laterally adjacent convolutions, then anchor the other end of the cord. With such a method the severance of a single convolution would cause the entire whipping cord to unwind. In accordance with the present invention, each convolution is knotted or twisted, and the possibility of the entire cord becoming unwrapped upon severance of one convolution is eliminated.

As best seen in Fig. 2, one end 12^a of the whipping cord is wrapped about the lowermost convolution of the cord, and the free end of the cord tucked under said convolution to serve as an anchor. The intermediate portion of the cord is then wrapped around the shaft forming a convolution 12^b immediately above and laterally adjacent the lowermost convolution 12^a. Before forming the third convolution, the intermediate portion of the whipping cord is twisted under and over convolution 12^b as indicated at 12^c. Another convolution is then wrapped about the shaft and a similar procedure is followed, each convolution including a twist or knot such as 12^c which sustains the individual convolution against unwinding when an adjacent convolution is severed.

I prefer to so arrange the twists or knots in the whipping cord, that the twist on one convolution will be closely adjacent the twist of another convolution. The twists

will thus produce a stepped or spiral appearance as indicated in Fig. 4 of the drawings.

Here the successive twists or knots produce a spiral rib about the whipping, and the finished club is of attractive appearance.

It will be evident from reference to Fig. 3, that cutting of the whipping cord at some point, such as the point 15, would not cause unwinding of either of the convolutions shown in Fig. 3, and that if either of the convolutions shown, were severed, the other convolution would remain intact, and would not unwind, due to the fact that it is self-locking against unwinding.

Various changes and alterations might be made in the general form and arrangement of parts described, without departing from the invention. Hence I do not wish to limit myself to the details set forth, but shall consider myself at liberty to make such changes and alterations as fairly fall within the spirit and scope of the appended claims.

25 I claim:

1. A method of whipping, which includes the steps of winding a cord in a series of laterally adjacent convolutions about an article to be whipped, and twisting the cord under each convolution before the next convolution is formed, whereby the cord is bound by each convolution and the convolutions individually hold the cord against unwrapping.

30 2. A method as set forth in claim 1, and wherein the twists are arranged adjacent each other in adjacent convolutions to produce a generally stepped or spiral series of twisted portions in the finished whipping.

3. A golf club including a shaft and a flexible element wrapped about the handle end of the shaft, a whipping cord wrapped about the shaft and one end of the flexible element to prevent unwinding of the flexible element, said whipping including a series of adjacent convolutions individually locked against unwrapping.

4. A golf club including a shaft and a flexible element wrapped about the handle end of the shaft, a whipping cord wrapped about the shaft and one end of the flexible element to prevent unwinding of the flexible element, said whipping including a series of adjacent convolutions individually locked against unwrapping, by passing the cord end under one convolution before forming the next convolution.

5. A golf club including a shaft and a flexible element wrapped about the handle end of the shaft, a whipping cord wrapped about the shaft and one end of the flexible element to prevent unwinding of the flexible element, said whipping including a series of adjacent convolutions individually locked against unwrapping, by passing the cord end under one convolution before forming the next convolution to form a spiral series of twists in the cord.

6. A golf club including a shaft, a leather strip spirally wound about the handle end of the shaft, a whipping cord lashing down the free end of the leather strip, and including a series of laterally adjacent convolutions, each having a twist therein to prevent unwinding of one convolution upon severance of an adjacent one.

WILLIAM P. LEVY.
